UNITED STATES PATENT OFFICE.

ITALO LERTORA, OF GENOA, ITALY

LIQUID-FUEL BURNER.

1,115,218.

Specification of Letters Patent. Patented Oct. 27, 1914.

Application filed July 21, 1913. Serial No. 780,252.

To all whom it may concern:

Be it known that I, ITALO LERTORA, mechanician, subject of the King of Italy, residing at Genoa, Italy, have invented certain new and useful Improvements in Liquid-Fuel Burners, of which the following is a specification.

This invention relates to an apparatus for burning liquid fuel such as tar, which has been atomized by two currents of steam or air, by means of a nozzle provided with a set of truncated and tapered passages of circular section diverging from the center of said nozzle.

The principal object of this invention is to provide a new and improved form of burner for liquid fuel, and one which will prevent the formation of unburned residues in the nozzle.

Other objects are to provide a simple and efficient means for regulating the flame, and also means whereby the burner may be readily cleaned.

The invention is illustrated in the accompanying drawings, in which:

Figure 1 is a vertical longitudinal section of the appliance; Fig. 2 is a side elevation thereof; Figs. 3 and 4 are end views of the appliance respectively from either end; Fig. 5 illustrates on a larger scale, a vertical longitudinal section of the nozzle, and of the flange in which provision is made for the subdivisions of the two currents; Fig. 6 illustrates a section on the line 2-2 looking in the direction of the arrows, of the pipe for the admission of the air in the center of the nozzle and in the flange containing the double set of passages.

An annular nozzle member 16 containing the annularly arranged, diverging nozzle outlets 4, is screw threaded into the outer casing 17 of the apparatus. Within the casing is mounted a rotatable forwardly tapering tube 10, having a flange 15 resting against the inner surface of the nozzle member 16. A rearwardly extending and diverging extension 14' on the flange 15 forms with the tube 10 an annular space 18, and with the outer casing, a chamber 8. Lead-ing from said annular space through the flange 15, is an annularly arranged series of passages 4' adapted to be brought into and out of register with the outlets 4, by rotation of the tube 10. A second annularly arranged series of passages 13 lead from the chamber 8 into the respective passages 4'.

In operation, the fuel is admitted to chamber 6 through pipe 5, while the steam or compressed air passes into chamber 2 through port 1. Into pipe 3 and chamber 7 there is led steam for feeding the ejector 11. In this way the fuel in chamber 6 is heated beforehand by the steam in chamber 7 and that in chamber 2. The liquid fuel flows through valve 12 and then is brought into chamber 8 under the action of the steam current proceeding from the ejector 11. Said chamber 8 is divided from chamber 2 for the injecting current by the extension 14' of the flange 15 in conjunction with the tube 10. Provision is made in the flange for the set of passages 13 for the subdivision of the injecting current and for the set of passages 4' and these latter, in the position at full power, form extensions of the passages 4 of the nozzle. The atomized fuel injected into the combustion chamber from the ring of nozzles 4 receives the air required for its combustion from a tapered tube 10 into which the air is led under pressure from a pipe 9. Said tube 10 can be turned by inserting a rod in the openings 14, or in any other convenient manner.

Having thus explained my invention, what I claim is:

1. An apparatus for burning liquid fuel, comprising a fuel chamber, means for supplying the fuel to the chamber, an outlet valve for said chamber, an ejector arranged adjacent to the outlet valve, means for supplying heated fluid to the ejector, a chamber into which the ejector forces the fuel, said chamber being provided with an annularly arranged series of outlet passages, a second annularly arranged series of passages, with which said first named passages respectively communicate, means for supplying steam to said last named passages, and means arranged centrally with respect to said passages for supplying air to the area of combustion.

2. An apparatus for burning liquid fuel, comprising a fuel supply chamber, having an outlet at one end thereof, a valve for controlling said outlet, a chamber for heated fluid at one side of said supply chamber, an ejector leading from said last named chamber and arranged at right angles to the fuel outlet, a second cylindrical chamber for heated fluid, arranged on the opposite side of the fuel chamber, a nozzle at one end of said second chamber having an annular se-

ries of diverging, truncated, conical, discharge passages, a rotatable air tube passing through said second chamber and nozzle, means for supplying air to said air tube, a flange carried by said air tube having passages communicating with said second chamber and adapted to be brought into and out of register with the discharge passages, and

means connecting the flange passages with the fuel ejector.

In testimony whereof I affix my signature in presence of two witnesses.

ITALO LERTORA.
